UNITED STATES PATENT OFFICE.

ELLIS GRABER, OF TUNBRIDGE WELLS, ENGLAND.

MACHINE FOR USE IN DRYING OR TREATING PHOTOGRAPHIC PRINTS, FILMS, AND THE LIKE.

Application filed December 4, 1922. Serial No. 604,937.

To all whom it may concern:

Be it known that I, ELLIS GRABER, a British subject and resident of 16 Newton Road, Tunbridge Wells, in the county of Kent, England, have invented certain new and useful Improvements in and Relating to Machines for Use in Drying or Treating Photographic Prints, Films, and the like, of which the following is a specification, such as will enable others skilled in the art to which it appertains to make and use the same.

This invention refers to improvements in or relating to machines for use in drying or treating photographic prints, films and the like, and it has for its primary object to provide a drying machine of improved and simplified construction, which will economize space and be capable of dealing in a continuous and in a rapid, efficient and automatic manner with a series of prints or length of paper or other material, such as delivered from a photographic developing and washing machine or from a roll.

In order that the present invention may be clearly understood and more readily carried into effect it is hereinafter described with reference to the accompanying drawings, in which:—

Figure 1 is a perspective view of the improved drying machine, with the side plates removed to better show the internal construction;

Figure 2 is a sectional side elevation of said machine corresponding to the preceding figure;

Figure 3 is a fragmentary perspective view of the drum showing the gearing and the internal mechanism, and

Figure 4 is a detail sectional view of the hollow trunnion shaft of the drum showing the electrical connections leading therefrom to portions of two of the rollers one of which is shown in section.

According to the present invention the improved machine comprises a series of revolving rollers *a* which are preferably internally heated and arranged between suitable side frames or guides or, as shown, between a pair of side plates or discs *b* so as to constitute a complete or partial drum or cage. In the latter case the said drum or cage is preferably mounted, so as to turn about a horizontal axis supported by hollow trunnions *c* from plummer blocks or other bear-

ings *d* suitably arranged on or supported from a framework *e* of angle iron or other suitable metal or material. The drum *b* and rollers *a* may be operated from any suitable source of power, the drive element of the apparatus being indicated as wheel *f*. Conveniently the drum itself *b* would be rotated at a slow speed by means of suitable reduction gearing *g*, *h*, *i* and *j*, and the rollers themselves would be provided with sprocket wheels *a'* at their ends in engagement with a chain *k* which may be driven by other suitable gearing from the main driving means, such as the spur wheels *l m n o p*, the former of which *l* is stationary, being loosely mounted on the hollow drum shaft *b'* and kept in position by part of the bearing being cut away, also part of the boss of the wheel, thus forming a dog, and the latter wheels *o p* being mounted on a shaft *q* carried by the drum plate *b*. These latter wheels obtain their movement by revolving round the fixed wheel. The rollers *a* are preferably heated in any desired manner and to any desired degree, as for example, electrically, as hereinafter described.

In operation the photographic paper *r* or the like to be dried would pass from the developing, fixing and washing machine (not shown) through a suitable squeegee or pair of rollers adapted to remove therefrom the surplus moisture. From thence the paper would pass over the upper periphery of the drum *a b* in the direction of the rotation of the latter and it would be in contact with the revolving rollers *a* throughout a convenient portion thereof, say for one half or three quarters of its periphery, or in other words in contact with from six to nine of the revolving rollers. From thence the paper *r* or the like would pass over one or more loose rollers *s* driven by frictional contact with the paper, and up on to a friction-driven winding-on spool or reeler *t* driven by a belt *t'* from the shaft 17 hereinafter referred to. This friction-driven reeler *t* also serves to keep the paper *r* or the like in good contact with the hot rollers according to the amount of friction required, the speed being identical with the output of the developing machine.

In practice the paper or the like to be dried may be passed from the washing machine say at the rate of one yard per minute, and the arrangement is such that the drum

itself $a\ b$ which could conveniently be about one yard in diameter, would make several revolutions per minute. Thus in its passage over the said drum the paper r to be dried 5 would be brought successively into contact with the whole series of rollers a several times, the surface speed of the machine being faster than the actual travel of the paper, the resulting drying capacity being equal to 10 that of a far larger machine. Another important feature of the present invention apart from the differential speed of the paper r and the drum $a\ b$ consists in the arrangement whereby the heated rollers a 15 are allowed a period of rest from contact with the wet or damp paper or the like being dried, thereby giving them a chance to heat up or recover before they come into contact with the wettest portion of the paper r as it 20 issues from the squeegee or moisture-removing rollers. Thus the wettest portion of the paper or the like being dried comes into contact with the hottest of the rollers a , which latter as the drying process takes place 25 gradually lose some of their heat and pass to that portion of the paper r which has been partly dried. Thus it will be seen that each heated roller does an equal share of drying, which is a great advantage.

30 A suitable cover or hood t' having an outlet u is provided to protect the machine and also to serve for the collection of the steam or other vapour arising during the drying process. The outlet u should be connected 35 with piping to draw the moisture out of doors. The drying process in addition to being effected by the heated rollers a , may also be assisted by streams of heated or cold air directed or blown on to one or both surfaces of the paper, as hereinafter more fully described, and by this means economy is also effected in the consumption of electricity, 40 gas or the like and a suitable atmosphere is maintained in the workroom. This air may also be used to assist in maintaining an efficient circulation of air through the drum $a\ b$ and the cover or hood t' and the elimination 45 of the moisture or steam. In order to still further assist in the extraction of moisture 50 and circulation of the air I may provide a pair of revolving vanes v' which are arranged one on each side of a central division plate v^2 and driven by a belt or the like v^3 on a pulley v^4 on the countershaft 17. The 55 air so used to assist the drying is preferably directed on to the paper r by means of the radially arranged distribution pipes v which are disposed so as to deliver the air between the revolving and heated rollers a 60 so that it does not detrimentally affect their efficiency by reducing their temperature. For materials not requiring the same amount of drying as wet photographic card, i. e., 65 gummed paper, coated paper and the like, the heat in the rollers a could be dispensed with,

the said rollers a being used only for supporting and carrying the paper r while the drying is effected by means of hot air being blown on to one or both sides of the paper.

In practice the heat of the revolving 70 rollers a and the speed of the drum $a\ b$ may be regulated to suit the requirements of the paper r or the like being dried, the former by means of a resistance switch. A pilot lamp is provided which when switched on 75 indicates whether the current is on or off and also when it is moderated to the various degrees. In the case where the rollers a are, as indicated, heated by electricity the rollers themselves and the chain sprocket wheels 80 a' thereon would be insulated as by the shouldered sleeve w from the trunnion shafts or end spindles x upon which they are adapted to revolve, and the electric current leads $y\ z$ could conveniently be coupled, 85 as shown in the lower portion of Fig. 4, so as to cause the current to pass into the machine by suitable leads $y'\ z'$ arranged within the hollow central trunnion or trunnions c and hollow shaft b' of the drum by 90 way of the terminals 10, 11, to suitable heating elements 12 arranged within the said rollers a . The rollers a and their heating elements 12 would also be so connected up on the end spindles x as to be readily interchangeable, and the insulating bodies of the heating elements themselves which are preferably connected up in series, would be provided with terminal sockets 13 adapted to engage projecting spindles or pins 14 95 provided as supports in connection with the ends thereof. The hollow trunnion shaft or axis b' of the drum $a\ b$ on the one side of the machine (not shown) would also serve for the introduction of the compressed 100 hot or cold air for drying, and on the other side, as described, for the introduction of the electricity, steam, gas, hot air or the like where such is used for the heating of the rollers a . By the means described and 105 shown where the drum $a\ b$ is electrically heated, no brushes or carbons need be used for making the electrical connections. The machine itself can also be made to operate bellows 15, or a dashpot by means of an eccentric 16 on a countershaft 17 and connections 18, 19 and thus provide the supply 110 of compressed air more satisfactorily and economically than a separate blower.

The above-described invention is particularly applicable in connection with photographic prints, gelatine or varnish-covered paper, coated paper, gummed papers, blue prints, films, fabrics and the like, as the heated drying rollers do not come into contact with the face of the paper. This feature will be appreciated from the photographic point of view as heat applied to the paper side of the picture and also the curvature given to the paper by the drum $a\ b$, 120 125 130

serves to counteract the natural tendency of the dried prints or paper *r* to curl up with the picture side inwards. It will also be seen that the heated rollers *a* owing to the fact that they themselves rotate and are rotated with the drum *a b* serve to present a continuously changing metallic ironing, drying or polishing surface to the whole of the underside surface of the paper, whilst at the same time by their arrangement which constitutes a duodecagonal drum, they cause the paper *r* to flap up and down in a lateral plane without affecting its length with regard to the feeding or rewinding arrangements which still further assists the drying process. The use of rotating and heated rollers *a* could also be adapted for glazing suitable paper if applied on the face side of the paper, as will be readily understood.

20 What I claim is:—

1. In a machine for drying and otherwise treating photographic prints, films and so forth, the combination comprising a shaft, a pair of plates mounted on said shaft, a plurality of rollers revolvably mounted between said plates, means for heating the prints and so forth on their passage over the rollers, and driving gear for said shaft and said rollers, said rollers being driven at a peripheral speed which differs from the speed of the prints and so forth around the rollers.

2. In a machine for drying and otherwise treating photographic prints, films and so forth the combination comprising a shaft, a pair of plates mounted on said shaft, a plurality of heated rollers revolvably mounted between said plates, the prints, films and so forth being adapted to be passed between the plates in contact with a plurality of said heated rollers, and driving means for said shaft and said rollers, the rollers being driven at a speed higher than the speed of movement of the plates, films and so forth.

45 3. In a machine for drying and otherwise treating photographic prints, films and so forth the combination comprising a shaft, a pair of plates mounted on said shaft, a plurality of heated rollers revolvably mounted between said plates, the prints, films and so forth being adapted to be passed between the plates in contact with a plurality of said heated rollers whilst the remaining rollers are not engaged by said prints and so forth, and driving means for said shaft and said heated rollers.

60 4. In a machine for drying and otherwise treating photographic prints, films and so forth the combination with claim 2 of a hood extending partially over the said heated rollers, and means connected to said hood for the collection and withdrawal of vapour during the operation of the machine.

65 5. In a machine for drying and otherwise treating photographic prints, films and so

forth, the combination comprising a hollow shaft, a pair of plates mounted on said shaft, a plurality of rollers revolvably mounted between said plates, driving means for said shaft and said rollers, a plurality of radial pipes communicating with said hollow shaft, and a plurality of perforated pipes connected to said radial pipes, said hollow shaft, radial pipes and perforated pipes serving for directing air on to the prints, films and so forth on their passage between the plates and over the rollers.

6. A machine for drying and otherwise treating photographic prints, films and so forth comprising a framework, a hollow shaft mounted in said framework, a pair of plates mounted on said shaft, a plurality of rollers revolvably mounted between said plates, gearing for said shaft and said rollers, a plurality of vanes revolvably mounted in said framework, driving mechanism for said vanes a plurality of radial pipes communicating with said hollow shaft, a plurality of perforated pipes connected to said radial pipes, bellows with means for connecting said bellows to the hollow shaft, and operating means for said bellows, said operating means being actuated by the gearing for the shaft and rollers.

7. In a machine for drying and otherwise treating photographic prints, films, and so forth, the combination comprising a shaft, a pair of plates mounted on said shaft, a plurality of trunnions on said plates, a plurality of rollers revolvably mounted on said trunnions, electric heating elements mounted inside said rollers and supported by said trunnions, means for supplying a heating current to said trunnions and to the heating elements, and means for rotating the shaft and the rollers.

8. In a machine for drying and otherwise treating photographic prints, films and so forth the combination comprising a hollow shaft, a pair of plates mounted on said shaft, a plurality of rollers revolvably mounted between said plates, means for rotating the hollow shaft and the rollers, a plurality of pipes radially mounted around said shaft, means for supplying compressed air to one end of said hollow shaft, the compressed air being adapted to be distributed over the prints, films and so forth passing around the rollers, means for supplying a heating medium to the other end of the hollow shaft, and means for conducting the heating medium to the interior of the rollers.

9. A machine for use in drying and otherwise treating photographic prints, films and so forth, comprising in combination a framework, a shaft mounted in said framework, a pair of plates mounted on said shaft, a plurality of rollers revolvably mounted between said plates, said rollers and plates constituting a drum over which

the prints and so forth are adapted to pass, means for revolving the rollers, means for revolving the cage, a winding on spool on which the prints are adapted to be wound, 5 means for frictionally driving said spool, means for heating the rollers, means for directing air on to the prints and so forth, and means for extracting the vapour arising during the passage of the prints and so 10 forth over the cage.

10. A machine for drying photographic paper comprising a framework, a shaft mounted in said framework, a pair of plates mounted in said shaft, a plurality of rollers 15 revolvably mounted between said plates, said rollers and plates constituting a cage over which the photographic paper is passed, driving means for said cage, a plurality of sprocket wheels mounted one on each roller, 20 a sprocket chain passing round said sprocket

wheels, means for driving said sprocket chain from the driving means for said cage, a winding-up roller for receiving the paper from the rollers, means for frictionally driving said winding-up roller, bellows and 25 pipes for directing air on to the paper, eccentric mechanism driven by the driving mechanism for the cage for operating the bellows, a plurality of vanes revolvably mounted in the framework and driving 30 mechanism therefor, and a hood on said framework covering some of the rollers, said hood having an outlet through which vapours are adapted to be removed.

In witness whereof I have hereunto set my 35 hand in presence of a witness.

ELLIS GRABER.

Witness:

HENRY FAIRBROTHER.
